UNITED STATES PATENT OFFICE.

ERIC G. LINDHE, OF NEW YORK, N. Y.

COATING SHEET METAL.

1,184,654.

Specification of Letters Patent. Patented May 23, 1916.

Application filed June 12, 1911. Serial No. 632,708.

To all whom it may concern:

Be it known that I, ERIC G. LINDHE, a subject of the King of Sweden, residing in the city of New York, borough of Manhattan, in the county and State of New York, have invented a certain new and useful Improvement in Coating Sheet Metal, of which the following is a specification.

The invention relates to the treatment of metal sheets preparatory to joining them in superposed condition in the production of shims or spacing-plates.

In U. S. Letters Patent No. 969,709, dated Sept. 6, 1910, is shown and described a shim of this character composed of a number of thin sheets joined on their adjacent faces to form a unitary mass which may be reduced in thickness when required by stripping one or more sheets from such mass.

The object of the present invention is to provide apparatus in which the cleansing of the sheets, coating with solder or other binder, and the application of a covering adapted to protect the surfaces from oxidation, may be performed rapidly and economically, with the necessary uniformity of deposition.

The invention consists in certain novel features of construction and arrangements of parts by which the above objects are attained, to be hereinafter described and pointed out in the claims.

The accompanying drawings form a part of this specification and show the invention as it has been carried out in practice.

Figure 1 is a side elevation of the entire apparatus. Fig. 2 is a corresponding vertical longitudinal section. Fig. 3 is a plan view of the same. Fig. 4 is a transverse vertical section through the cleaning tank as on the line 4—4 of Fig. 2. Fig. 5 is a similar view through the melting-pot, taken on the line 5—5 in Fig. 2. Fig. 6 is an end elevation of the feeding mechanism, with certain portions omitted. Fig. 7 is an end view of the melting-pot. Fig. 8 is an elevation of a pair of feeding rolls or pulleys. Fig. 9 is an end view showing a detail of the feeding mechanism. Fig. 10 is a corresponding plan view. The remaining figures are on a larger scale. Fig. 11 is an elevation of the cutting-off mechanism. Fig. 12 is a corresponding vertical section. Fig. 13 is

an elevation of the mechanism employed for applying the non-oxidizing covering. Fig. 55 14 is a corresponding vertical section.

Similar letters of reference indicate the same parts in all the figures.

The material to be treated may be understood to be thin brass which is fed or drawn 60 from a roll, passed through an acid or other cleaning bath, then coated on both faces with a binder of soft solder, and the protecting covering applied; the strip is then cut off in the desired short lengths.

When piled for the uniting treatment, the coated sheets are alternated with uncoated sheets, the solder on both faces of the former being sufficient to join them to the latter, and therefore the apparatus is arranged 70 to be easily changed for a run of material through the cleaning bath, heated, but not coated, and the protective covering applied as before and the strip cut to lengths. As the material is extremely thin it is preferably fed by drawing it through the several parts of the apparatus to the point of cutting off.

A is a frame or table carrying at one end notched standards A¹ receiving screw-threaded rods B extending through nuts B¹ and having conical heads B² adapted to engage the opposite ends of a tubular core M¹ on which the roll M of thin material is closely wound, and thus hold the latter in 85 position to be drawn off by revolving between the conical heads B² serving as centers, and by means of the nuts B¹ permitting the tension to be controlled.

Mounted in the table A is a tank or receptacle C containing dilute acid or cleaning solution, and provided with a cover C¹ having on its under face a depending frame C² in which is supported two transverse tubes C³ C⁴, one, C³ is slotted longitudinally along 95 its upper face, and the other, C⁴, similarly slotted along its lower face, and both loosely filled with wicking which protrudes through the slots, and at the ends of the tubes dips into the acid. The wicks serve to apply acid 100 to both faces of the thin metal strip which enters beneath the rear end of the cover C¹, passes over and in wiping contact with the wick in the tube C³, under the tube C⁴, across its wick, and emerges beneath the front end 105 of the cover and passes over a rod C⁵ to the

melting-pot D mounted in the same table A. The melting-pot is received in a holder or heating-chamber D¹ and is heated by suitable gas-burners D² or otherwise. The pot is provided with a cover D³ having depending arms d³ on its under face in which are supported a transverse rod D⁴ and transverse tubes D⁵ D⁶. This cover acts to retain the heat of the molten bath immediately over the surface thereof, so that the metal strip moistened by the cleaning solution is heated at its surface before being immersed in the molten solder, which removes the cleaning solution and coats the freshly cleaned surface out of contact with the air. The strip from the rod C⁵ passes beneath the rear edge of the cover D³ and thence under the rod D⁴ lying beneath the surface of the melted solder and on leaving the latter passes beneath the tube D⁵ and over the tube D⁶; the tubes D⁵ D⁶ are preferably of copper and are heated by radiation from the melted metal and by currents of hot products of combustion passing through them from the heating-chamber. Each has a longitudinally arranged fin D⁷, preferably of aluminum, serving as a scraper, the fin on the tube D⁵ projecting downwardly and the other on the tube D⁶ upwardly. d⁶ is a tubular connection from the heating chamber D' as seen in Fig. 5, for supplying heat from the said chamber to the tube D⁶.

The strip on emerging from the solder passes beneath the tube D⁵ and over the tube D⁶ and thence out through the space beneath the forward end of the cover D³. Surplus solder is removed by the fins D⁷ and falls back into the pot, the fins remaining clean by reason of the fact that solder will not adhere readily to aluminum. Copper is preferred for the tubes D⁵ D⁶ because of its good heat conducting properties which serve in keeping up the temperature of the fins or scrapers.

If the strip is not to be coated but subsequently cut up into lengths to be piled between two coated lengths, it is led through the cleaning bath as before but passes immediately below the cover of the melting-pot and not through the bath of melted metal. The utility of passing the material below the cover without immersing is that some strips are not to be coated with solder but are to lie between two solder-coated sheets, such sheets are drawn through below the cover to heat them, or rather the strip to be cut into sheets, so that they will be warm enough to melt the resin and thus protect their cleaned surfaces from oxidation, ready to join the soldered surfaces by the adjacent sheets. In either case it is necessary to apply a covering or film to protect the surface against oxidation and thus insure uniform adhesion over the entire

surfaces when the solder is melted to unite the mass. This protection may be attained by the use of various materials; thin cakes or plates E of resin suitably mounted to contact with both faces of the strip as it is drawn between them while still warm will serve the purpose. As the strip is very thin it is extremely difficult to guide, and it has been found preferable to mount the plates or cakes E with liberty to follow the lateral movements of the strip rather than attempt to control the latter.

E¹ is a vertical frame or flat pocket adapted to receive loosely the two cakes E E, mounted on grooved rollers E² running on a track E³ on a supporting plate E⁴ having apertures e e adapted to receive fixed horizontally extended rods on which the plate is carried. A transverse slot e¹ in each face of the frame E¹ receives the strip M with one cake above and the other below it and the cakes are pressed against the surfaces by a loop or belt E⁵ lying upon the upper edge of the upper cake and beneath the lower edge of lower cake with the bight E⁶ at each side passed over a pulley E⁷ mounted on the frame E¹ and partially encircling a free pulley E⁸ from which is suspended a tension weight E⁹.

E¹⁰ E¹⁰ are braces on the supporting plate E⁴ and having rollers E¹¹ on their upper ends arranged to roll upon the upper portion of the forward face of the frame and permit the latter to move laterally, and E¹² E¹² are similar braces fastened to the rear face of the plate E⁴ with their upper ends lying against the rear face of the frame. Thus arranged the strip is pulled through the slots e¹ between the adjacent edges of the resin-cakes with its temperature high enough to melt the resin slowly while in contact therewith and thus completely cover both faces of the strip with a thin film sufficient to protect the surfaces against oxidizing or harmful results of handling. The belt E⁵ and its weights E⁹ serve to hold the cakes yielding against the strip with uniform pressure and feed them toward each other as they are slowly consumed. The rollers E² permit the frame to move laterally in accommodating itself to the movements of the thin strip M.

The rods on which the plate E⁴ is mounted may be those marked A² A² on the front of the table A, to be used when the strip is to be cleaned and warmed but not coated with solder, and is therefore mounted near the melting-pot so that the strip will retain sufficient heat to affect the cakes, or, in the case of the coated strip in which the temperature is higher, the rods may be those marked A³ A³ located at a greater distance from the melting-pot on the stand A⁴ to allow the temperature to lower enough to harden the coating before passing be-

tween the cakes. The location and length of the rods A^2 A^3 permit the frame E^1 to be adjusted to present the strip in either case at the desired temperature. The supporting plate E^4 and pocket or frame thereon may be easily transferred to either pair of rods as found necessary or desirable.

The stand A^4 carries the feeding and cutting-off mechanisms. Experiment has demonstrated the great difficulty of guiding strips of the extremely thin material used, two one-thousandths of an inch being the preferred thickness, and the impracticability of running such material in straight paths by means of gripping rolls. The feeding mechanism shown comprises two pairs of horizontal pulleys F F^1 mounted in standards A^5 A^6 with a belt F^2 running on the uppermost of each pair and a similar belt F^3 running on the lowermost; the pulleys F F^1 of each pair are separated sufficiently to avoid gripping the strip M between them, as are also the adjacent faces of the belts. The midlength portion of the upper member or stretch of the lower belt F^3 is slightly raised and supported on a plane bed F^4 having its ends curved slightly downward, and the lower member of the upper belt F^2 is pressed downward toward the bed F^4 by rollers F^5 F^6 mounted in pivoted arms F^6 F^6 drawn downward by springs F^7 into contact with the other belt member. The belts travel at the same speed and are driven by a shaft F^8 through a pinion, not shown, in mesh with a gear-wheel F^9 on the shaft of the lower forward pulley F^1 which in turn is in mesh with a similar gear-wheel F^{10} on the shaft of the upper pulley F of the same pair. The strip M is engaged frictionally by the flat adjacent surfaces of the belts, thus lightly grasping the strip between broad areas of the moving belts which are flexible enough to be unaffected by slight surface corrugations or irregularities in the strip and successfully carry the latter forward in the straight path of the belts even though the edge of the strip may be waved or otherwise irregular, with a grip of sufficient force to pull the strip from the roll at the rear end of the apparatus and through the various parts in which it is treated.

The cutting-off mechanism is at the forward end of the stand A^4 and consists of a fixed lower knife G mounted on the stand with its cutting edge flush with a rearwardly extending shelf G^2 , and a slide G^3 mounted on vertical pillars A^{15} A^{15} , carrying a spring presser-foot G^4 and the upper knife G^1 . At the top of each pillar A^{15} is an extension or stud A^{16} of smaller diameter, encircled by a helical spring G^5 abutting at the upper end against the interior of the slide and having sufficient strength to raise the latter and its attachments.

G^6 G^6 are links pivoted one on each side

to the slide G^3 near the top, and pivotally connected at the lower ends to levers G^7 G^7 pivoted to the stand at g . Each lever carries a roller G^8 in the path of a nose or projection G^9 on a cam-disk G^{10} mounted on the shaft of the forward upper pulley F . At each revolution the projections G^9 strike the rollers G^8 and depress the levers which through the links G^6 draw the slide G^3 downward, the spring presser-foot momentarily arresting the forward movement of the strip M during the descent of the upper knife G^1 by which the strip is severed; the end of the thin strip between the contacting portions of the belts F^2 F^3 and the presser-foot G^4 may buckle slightly during this cutting-off movement but as it is almost instantaneously performed is not injurious. The slightly buckled end immediately straightens by its own elasticity and passes on between the knives to be cut off at the completion of the next revolution. The severed length is received in a chute A^7 and directed to any suitable receptacle or to a traveling apron, not shown, to be delivered for further treatment.

Runs are made by the apparatus to produce a desired number of lengths of cleaned, solder-coated, and covered material, and is then changed, as before described, to produce the desired number of lengths of cleaned and covered material without the solder coat. These lengths are subsequently piled or assembled and treated by suitable apparatus and methods to unite them in plates from which the shims, washers, or other spacing-plates may be cut by dies or otherwise.

In the present apparatus the steps of the process include, in one case, cleaning in a suitable bath, heating to a degree sufficient to melt the material serving as a protecting covering, applying such covering, and cutting into lengths. In the other case or arrangement the steps comprise, the cleaning, coating with solder, and while heated applying the protective covering, and the cutting-off.

I claim:—

1. The process of coating a sheet which comprises applying a molten coating material to the strip, heating the strip thereby, and softening a second material by contact with the heated, coated strip to form a second coating.

2. The process of coating a sheet which comprises applying a cleaning solution to the surface of the sheet, coating the strip with molten metal, and then applying a second coating material by contact with the heated strip to soften said second material and spread it over said first coating.

3. The process of coating a strip which comprises applying a molten coating to said strip, cooling the coating slightly, and then

applying a second coating material by contact with the strip to soften said second material and spread it over said first coating.

5 4. The process of applying a composite coating to a metal sheet which comprises coating the sheet with a molten material of relatively high melting point and then fusing a second coating of relatively low melting point on said first coating by the residual heat of said first coating.

10 5. The process of applying a composite coating to a metallic sheet which comprises coating the sheet with a molten metallic material of a relatively high melting point and heating the strip, partially cooling said coating, and then fusing a second coating of non-metallic material of relatively low melting point by the residual heat of said 20 first coating.

6. The process of applying a composite coating to a sheet which comprises applying a cleaning solution to the surface of the sheet, then coating the sheet with a molten material of relatively high melting point to remove the cleaning solution and heat the strip, partially cooling the coating, and then forming a second coating of lower melting point by fusing it on said first coating by 25 the residual heat of said first coating.

7. The process of cleaning and coating a metal sheet which comprises applying a cleaning solution to the sheet, heating the sheet, and then applying a coating material 30 to the sheet while moistened by the cleaning solution to simultaneously remove the impurities and coat the sheet.

8. The process of cleaning and coating a metal sheet which comprises applying a 40 cleaning solution to the sheet, heating the sheet while moistened by the cleaning solu-

tion, and then coating the sheet while heated and moistened.

9. The process of cleaning and coating metal sheets which comprises applying a 45 cleaning solution to the surface of the sheet, heating the sheets while moistened by the cleaning solution, and softening the coating material by contact with the heated strip to form a coating therefor. 50

10. The process of treating continuous strips of thin metal, which consists in cleaning, heating, and then, while in a heated state, passing the strips between loosely mounted cakes of material and softening 55 them and covering the surfaces of said strips therewith.

11. The process of treating continuous strips of thin metal, which consists in cleaning, coating with melted coating material, removing the surplus coating material, passing the strips between loosely mounted cakes of coating material while still warm, and by the heat thereof softening the same and causing it to adhere while in such condition 60 to the surfaces of said strips. 65

12. The process of coating sheet metal which comprises passing the sheet through a bath of molten metal of relatively high melting 70 point, partially cooling the coating, passing the sheet through a second coating material of relatively low melting point and utilizing the residual heat of the first coating operation in effecting the second coating operation. 75

In testimony that I claim the invention above set forth I affix my signature, in presence of two witnesses.
